US00D981962S

(12) United States Design Patent (10) Patent No.: US D981,962 S
Fu et al. (45) Date of Patent: * Mar. 28, 2023

(54) SOCKET

(71) Applicant: SCHNEIDER ELECTRIC (AUSTRALIA) PTY LTD, Macquarie Park (AU)

(72) Inventors: Jiayu Fu, Shenzhen (CN); Fuhua Shan, Shenzhen (CN); Pei Shang, Shenzhen (CN)

(73) Assignee: SCHNEIDER ELECTRIC (AUSTRALIA) PTY LTD, Macquarie Park (AU)

() Term: 15 Years

(21) Appl. No.: 29/806,139

(22) Filed: Sep. 1, 2021

Related U.S. Application Data

(62) Division of application No. 29/703,917, filed on Aug. 30, 2019, now Pat. No. Des. 962,172.

(57) CLAIM

The ornamental design for a socket, as shown and described.

DESCRIPTION

FIG. 1 is a front view of the socket, showing my new design.

FIG. 2 is a back view thereof.

FIG. 3 is a top view thereof.

FIG. 4 is a bottom view thereof.

FIG. 5 is a left side elevational view thereof.

FIG. 6 is a right side elevational view thereof.

FIG. 7 is a front perspective view thereof; and,

FIG. 8 is a back perspective view thereof.

The masked areas adjacent to the dash-dot broken lines in the drawings depict portions of the socket that form no part of the claimed design. The dash-dot broken lines define the bounds of the claimed design and form no part thereof.

1 Claim, 7 Drawing Sheets
